US00D333134S

United States Patent [19]

Aderman

[11] Patent Number: Des. 333,134

[45] Date of Patent: ** Feb. 9, 1993

[54] FRONT PANEL FOR A MEDIA ENCLOSURE
FOR A DATA PROCESSING SYSTEM

D. 307,423 4/1990 Hill D14/115
D. 308,672 6/1990 Aderman et al. D14/115
D. 313,982 1/1991 Eilert et al. D14/115
D. 314,568 2/1991 Martin D14/115

[75] Inventor: Wayne L. Aderman, Zumbro Falls, Minn.

Primary Examiner—Wallace R. Burke

Assistant Examiner—Freda S. Nunn

Attorney, Agent, or Firm—Roy W. Truelson; J. Michael Anglin

[73] Assignee: International Business Machines Corporation, Armonk, N.Y.

[57] CLAIM

The ornamental design for a front panel for a media enclosure for a data processing system, as shown and described.

DESCRIPTION

FIG. 1 is a front elevational view of a front panel for a media enclosure for a data processing system showing my new design;

FIG. 2 is a right side elevational view thereof, the left side elevational view being identical in appearance; and, FIG. 3 is a top plan view thereof.

The undisclosed rear elevational and bottom plan views are unornamented.
